(57) **CLAIM**

The ornamental design for a grill accessory, as shown and described.

DESCRIPTION

FIG. 1 is a front perspective view of a grill accessory, showing my new design;

FIG. 2 is a front elevation view thereof, with a rear elevation view being a mirror image thereof;

FIG. 3 is a right-side elevation view thereof;

FIG. 4 is a left-side elevation view thereof;

FIG. 5 is a top plan view thereof; and,

FIG. 6 is a bottom plan view thereof.
